UNITED STATES PATENT OFFICE.

JAMES W. BLAIR AND EROTAS H. WILDER, OF BROOKLYN, WISCONSIN.

CHEESE-DRAINING TABLE AND MOLD.

SPECIFICATION forming part of Letters Patent No. 253,835, dated February 21, 1882.

Application filed December 28, 1881. (No model.)

To all whom it may concern:

Be it known that we, JAMES W. BLAIR and EROTAS H. WILDER, of Brooklyn, in the county of Green and State of Wisconsin, have invented certain new and useful Improvements in Cheese-Draining Tables and Molds; and we do hereby declare that the following is a full, clear, and exact description of the invention, which will enable others skilled in the art to 10 which it appertains to make and use the same, reference being had to the accompanying drawings, which form a part of this specification.

Figure 1 is a perspective view, showing the molds in position upon the draining-table. Fig. 15 2 is a longitudinal vertical sectional view, showing the table ready to be reversed or turned. Fig. 3 is a vertical cross-section, and Fig. 4 is a perspective view, of one of the molds detached.

20 Corresponding parts in the several figures are denoted by like letters of reference.

This invention relates to molds and draining-tables for the manufacture of Limburger cheese; and it consists in certain improvements 25 in the construction of the same, which will be hereinafter fully described, and particularly pointed out in the claims.

In the drawings hereto annexed, A represents one of the draining-tables, which may be 30 of any suitable size, and provided with a surrounding rim or flange, B. One or more openings, C, should be provided at one end of the table, in order to permit the escape of the whey draining off from the cheeses supported 35 upon the table. The latter is provided at the ends with half-round pivots D.

The molds consist of square frames E, having longitudinal partitions F, each division or compartment being of the width of a cheese. 40 The sides of the frames and partitions have vertical grooves G, to admit a knife or cutter, by which the cheese, when sufficiently hard, may be cut into pieces of the proper size previous to being salted. Each mold consists of two of 45 the frames E, fitted together and connected by dowels H. A loose bottom, I is similarly connected to the under frame.

The draining-table is supported by its pivots D in suitable bearings in a frame, or a pair 50 of horses, J. To prevent the table from turn-

ing over, the said frame or horses is provided with springs K abutting against the under side of the table. Said springs may, however, be pressed or drawn back when it is desired to turn the table upon its pivots.

In operation the curd is dipped from the vat into the molds, which are then placed upon the draining-table. The upper section of each mold is then removed, and a second draining-table is placed upside down over the first table and the molds supported thereupon. The half-round pivots of the two tables are now connected by loose rings or sleeves, which may be easily slipped over them, the springs K are pressed back and the tables quickly turned 65 over, thus leaving the cheeses and molds in a reversed position upon the second table. The bottom of each mold may now be removed and, together with the upper section, taken away and washed for future use. The cheeses are 70 left upon the table until evening, when the table is again reversed. In the morning following the cheeses are cut into squares of the proper size by means of a suitable knife or cutter, guides for which are formed by the grooves 75 G in the molds. The latter are then removed, and the cheeses are now ready for salting and treatment in the usual manner.

By our invention larger molds than have heretofore been used may be conveniently handled. It has also been necessary in the manufacture of Limburger cheese as at present carried out to turn each individual cheese several times and to divide them from each other, or pigeon-hole them upon the draining-table by a 80 peculiar arrangement of loose boards. This is by our invention avoided, and an entire tableful of cheeses may be turned by a single movement, leaving the cheeses in a more perfect shape than by handling them individually, and 85 saving time and trouble.

In lieu of the straw usually placed under the cheeses to facilitate the draining, we propose to use a piece of coarse cloth or burlap, which presents a smoother surface and is more easily 90 kept clean.

Having thus described our invention, we claim and desire to secure by Letters Patent of the United States—

1. The herein-described draining-table A, 100

having rim or flange B, openings C, and half-round pivots D, in combination with a suitable frame or support, substantially as and for the purpose set forth.

5 2. The herein-described mold, consisting of a pair of frames, E, having longitudinal partitions F, the sides of which and of the frames are provided with vertical grooves G, and a loose bottom, I, said bottom and frames being connected by dowels H, substantially as and for the purpose set forth.

3. The combination of the supports J, hav-

ing springs K, with a pair of draining-tables A A, having half-round pivots D, and the molds E, held between said tables, substantially as and for the purpose set forth.

In testimony that we claim the foregoing as our own we have hereto affixed our signatures in presence of two witnesses.

JAMES W. BLAIR.
EROTAS H. WILDER.
